US0D1112767S

(12) **United States Design Patent** (10) **Patent No.:** **US D1,112,767 S**
(45) **Date of Patent:** **** Feb. 10, 2026**

(54) **PATCH ASSEMBLY**

(71) Applicant: **DBV Technologies**, Montrouge (FR)

(72) Inventors: **Pascale Ehouarn**, Gometz-le-Châtel (FR); **Jérôme Villette**, Le Plessis-Robinson (FR)

(73) Assignee: **DBV Technologies**, Montrouge (FR)

(**) Term: **15 Years**

(21) Appl. No.: **30/000,266**

(22) Filed: **Apr. 21, 2025**

Related U.S. Application Data

(60) Continuation of application No. 29/918,328, filed on Nov. 27, 2023, now Pat. No. Des. 1,076,110, which is a division of application No. 29/877,589, filed on Jun. 8, 2023, now Pat. No. Des. 1,012,296, which is a division of application No. 29/811,898, filed on Oct. 18, 2021, now Pat. No. Des. 999,385.

(57) **CLAIM**

The ornamental design for a patch assembly, as shown and described.

DESCRIPTION

FIG. 1 is a perspective view of a patch assembly;

FIG. 2 is a first side view thereof;

FIG. 3 is a second side view thereof;

FIG. 4 is a third side view thereof;

FIG. 5 is a fourth side view thereof;

FIG. 6 is a top view thereof;

FIG. 7 is a rear view thereof; and,

FIG. 8 is an exploded perspective view thereof.
